Patented Dec. 20, 1921.

UNITED STATES PATENT OFFICE.

JOHN BOROS, OF MILWAUKEE, OREGON, ASSIGNOR TO PERFECTION TIE COMPANY, OF PORTLAND, OREGON.

NECKTIE-HOLDER.

1,400,858.

Specification of Letters Patent. Patented Dec. 20, 1921.

Application filed February 15, 1921. Serial No. 445,143.

To all whom it may concern:

Be it known that I, JOHN BOROS, a citizen of the United States, residing at Milwaukee, in the county of Clackamas and State of Oregon, have invented a new and useful Necktie-Holder, of which the following is a specification.

This invention relates to cravats, it being the primary object of the invention to provide means whereby the usual four-in-hand string cravat may be converted into a made-up cravat, thereby eliminating the wear usually directed thereto in the tying and untying of the cravat.

15 A further object of the invention is to provide a slideable body portion mounted on a flexible support, the body portion forming a base to accommodate the knot of the cravat, whereby the tie may be slid with the

20 body portion.

A further object of the invention is to provide resilient means within the body portion for clamping the flexible support and eliminating any possibility of the knot moving accidentally, with respect to the collar associated therewith.

Another object of the invention is to provide a body portion of this character wherein all cloth engaging portions thereof will be especially constructed to eliminate wear on the cloth material associated therewith, to increase the life of the cloth material.

A still further object of the invention is the provision of a support having novel means for securing the spring member thereto, thereby insuring against the spring member becoming displaced and lost from the support to render the device inoperative.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

50 Referring to the drawing:—

Figure 1 is an elevational view of the device forming the subject matter of the present invention and illustrates the manner of supporting the cravat thereon.

Fig. 2 is a side elevational view of the slideable body portion. 55

Fig. 3 is a sectional view taken on line 3—3 of Fig. 2.

Fig. 4 is a vertical sectional view through the body portion of the tie support. 60

Fig. 5 is a detail view of the free ends of the legs of the supporting member.

Fig. 6 is a fragmental detail view of one of the eyelets of the supporting member, the same being shown in section. 65

Referring to the drawing in detail, the slideable cravat support includes a body portion 5 formed of suitable flexible sheet metal material and having its side edges extending inwardly to provide guideways for the flexible supporting member 6 associated therewith, and to be hereinafter more fully described. 70

The body portion 5 is bent intermediate its ends to provide opposed legs, each of 75 which being provided with an inwardly extending flange indicated at 7, the flanges being shown as extending toward each other. The spring member 9 is formed preferably of wire material, circular in cross section, 80 eliminating all sharp edges, and thereby presenting a structure to preserve the life of the cloth material or flexible supporting member associated therewith, and as shown, this spring member is supported within the 85 body portion of the support. The spring member 9 has loops 8 formed at the ends thereof, which loops are secured to the body portion 5 by means of the flanges 7 which are bent over one of the arms of the loops 90 to secure the spring member 9 against movement with respect to the support. To further insure against displacement of the spring member 9, the outer corners of the flanges 7 are bent into engagement with the 95 leg portions as at 12, and since the loop members 8 are disposed adjacent to each other, it will be seen that the flexible supporting member 6 may be passed readily therethrough. The spring member 9 normally exerts a lateral pressure on the loop portions to cause the flexible supporting member 6 to be gripped between portions of the loop members to retain the same 100 against movement.

Each of the leg members is provided with an opening 10 adjacent to the upper end thereof, which openings are of particular

constructions as clearly indicated by Fig. 6 of the drawing, wherein the edges of the openings are turned inwardly to provide smooth cloth engaging portions thereby reducing wear directed to the cloth associated therewith to a minimum.

This flexible supporting member 6 passes through the openings 10 where the same is positioned between the leg members thereof, 10 the intermediate portion of the flexible supporting member being formed into a loop to be positioned within the collar of the user, to connect the flexible supporting member thereto.

15 The free ends of the flexible supporting member 6 are secured to the lower portion of the cravat as by means of the pin 11, thereby preventing the flexible supporting member from being drawn through the body 20 portion or support 5 to disconnect the flexible supporting member 6 and the support 5, when the cravat is being removed from the neck of the wearer.

In the use of the device, the usual cravat 25 is tied around the body portion 5 so that the knot thereof completely houses the body portion 5. The flexible supporting member 6 is now positioned within the collar of the wearer, whereupon the knot is slid upwardly 30 to a position in proximity with the collar.

It is to be understood that during the movement of the knot, the fingers of the operator grasp the knot and force the leg members of the support 5 inwardly to release 35 the grip of the loop members 8 on the flexible supporting member 6. When the leg members have been released by the operator,

the loop members 8 frictionally engage the flexible supporting member 6 to retain the same in its adjusted position.

Having thus described the invention, what is claimed as new is:—

1. In a cravat support, a flexible supporting member, a supporting member including opposed legs positioned on the flexible supporting member, a spring member having loops formed at its ends and secured to the supporting member, said loops adapted to accommodate the flexible supporting member, the walls of said loops adapted to grip the flexible supporting member to restrict movement of the supporting member with respect to the flexible supporting member.

2. In a cravat support, a flexible supporting member, a supporting member having openings to accommodate the flexible supporting member, a spring member positioned in the supporting member, and secured thereto, said spring member having loop members formed at the ends thereof, 60 said loop members adapted to accommodate the flexible supporting member to grip the flexible supporting member, and said loop members adapted to restrict movement of the supporting member over the flexible supporting member.

In testimony that I claim the foregoing as my own, I have hereto affixed my signature in the presence of two witnesses.

JOHN BOROS.
